Primary Examiner — Manpreet Matharu*Assistant Examiner* — Yolanda Robinson(57) **CLAIM**

The ornamental design for a probe handle, as shown and described.

DESCRIPTION

FIG. 1 is a left, front and top perspective view of a probe handle, showing our new design;

FIG. 2 is a right, back and bottom perspective view of the probe handle of FIG. 1;

FIG. 3 is a left side view of the probe handle of FIG. 1;

FIG. 4 is a front view of the probe handle of FIG. 1;

FIG. 5 is a right side view of the probe handle of FIG. 1;

FIG. 6 is a back view of the probe handle of FIG. 1;

FIG. 7 is a top view of the probe handle of FIG. 1; and,

FIG. 8 is a bottom view of the probe handle of FIG. 1.

The broken lines immediately adjacent the shaded areas represent the bounds of the claimed design; the broken lines form no part of the claimed design.

1 Claim, 5 Drawing Sheets(56)
